UNITED STATES PATENT OFFICE.

WILL T. STATES AND HERBERT F. LAPP, OF CLEVELAND, OHIO.

BOWLING-PIN SETTER.

1,217,235.

Specification of Letters Patent. Patented Feb. 27, 1917.

Application filed November 14, 1916. Serial No. 131,285.

To all whom it may concern:

Be it known that we, WILL T. STATES and HERBERT F. LAPP, citizens of the United States, residing at Cleveland, in the county of 5 Cuyahoga and State of Ohio, have invented new and useful Improvements in Bowling-Pin Setters, of which the following is a specification.

The invention relates to bowling pin set- 10 ters.

The primary object of the invention is the provision of a setter of this character wherein the same is arranged within a bowl- 15 ing alley and will automatically place the pins upon the alley in the same position each time the setter is operated, thereby eliminating the hand setting of the pins and also the possibility of irregularity in the positioning of the pins upon the alley.

Another object of the invention is the provision of a setter of this character wherein each pin is brought to upright position automatically and centered so that it will be accurately placed or spotted upon an alley 25 with despatch.

A further object of the invention is the provision of a setter of this character wherein the construction thereof is novel in form so as to assure the accurate spotting or posi- 30 tioning of the pins automatically with despatch.

A still further object of the invention is the provision of a setter of this character which is simple in construction, thoroughly 35 reliable and efficient in its operation, strong, durable and inexpensive in manufacture.

Other objects will be in part obvious and in part hereinafter set forth.

The invention accordingly consists in the 40 features of construction, combination of elements and arrangement of parts which will be exemplified in the construction herein- after described, and the scope of the applica- 45 tion of which will be indicated in the appended claims.

In the accompanying drawings:

Figure 1 is a top plan view of a pin set- 50 ter constructed in accordance with the in- vention;

Fig. 2 is a front elevation showing the alley in vertical section;

Fig. 3 is an enlarged fragmentary verti-

cal longitudinal sectional view showing the setter in normal raised position;

Fig. 4 is a similar view in lowered posi- 55 tion;

Fig. 5 is a fragmentary vertical trans- 60 verse sectional view;

Fig. 6 is a sectional view on the line 6-6 65 of Fig. 1;

Fig. 7 is a sectional view on the line 7-7 70 of Fig. 1.

Similar reference characters indicate cor- 75 responding parts throughout the several views of the drawings.

Referring to the drawings in detail, A 80 designates a portion of the bowling alley which is of the ordinary well known construction, and B designates generally the 85 bowling pin setter which is located at the closed end of the alley and the details and operation of which will be hereinafter fully described. The pin setter comprises a vertically movable main frame 10 which is suspended over the bed of the alley A in the usual well known manner for the raising 90 and lowering thereof, while fixed at desirable points in the alley A and countersunk within the bed thereof are guide ferrules or plates 11, through which slide vertical 95 guide stems 12 fixed to the frame 10, the alley A beneath the plates or ferrules 11 being formed with sockets 13 for the said stems or rods 12 for accommodating the same, and these stems or rods 12 serve to 100 guide the main frame in its vertical movement with trueness for the accurate setting of the bowling pins in a manner presently described.

Arranged on the frame 10 at the upper 105 face thereof are longitudinally disposed tracks 14 upon which travel anti-friction rollers 15 journaled in a pin rack 16 supported for horizontal movement upon said frame, and this rack 16 is of the nest type, 110 that is to say, it is formed with a series of pockets 17 corresponding to the number of 115 bowling pins used in the playing of the game, and these pockets 17 are located in accordance with the proper spotting or set- 120 ting of the pins upon the alley, the frame 10 being formed with openings 18, each per- 125 mitting the dropping of a bowling pin C therethrough on to the alley A when the

rack 16 has moved the series of pins to upright position after the pins have been carelessly placed within the pockets 17 in said rack which is automatically moved in a 5 manner presently described.

Swingingly depending from the bottom of the frame 10 adjacent to and at circumferentially and regularly spaced points relative to the margin of the openings 18 there- 10 in are automatically adjustable pin guides 19 which are supported by springs 20 connecting them to the frame and are formed with beveled contacting ends 21 for engagement with the surface of the alley A when 15 the frame 10 is lowered so as to bring the guide 19 into proper position automatically for the centering of the pin C when dropped through the openings 18 and thereby locating each pin exactly over the spot upon the 20 alley and in upright position thereon. The guides 19 on the upward movement of the frame 10 swing upon the springs 20 away from each other to the position shown in Fig. 2 of the drawing, and on the lowering 25 of the frame said guides 19 are automatically moved to downwardly convergent relation to each other by the contact thereof with the surface of the alley A as is clearly shown in Fig. 3 of the drawings, and in 30 this position set the pins upon the spots and in upright position on the alley.

Mounted in the frame 10 at suitable points are vertically disposed guide sleeves 22 in which are slidably fitted operating plungers 23 carrying at their lower ends shoes 24 for contact with the surface of the alley A. Carried by the frame 10 are hangers or bearings 25 in which are pivoted rocking bell crank levers 26. To one end of each is 40 pivoted a link 27 which is also pivoted to the shoe 24 and to the other end of said bell crank levers 26 is pivotally connected a link 28, the same being also pivoted to the rack 17 so that on the lowering of the frame 10 45 the shoes contact with the alley A and the bell crank lever 26 is rocked in its hanger or bearing 25 to act upon the link 28, causing the rack 17 to slide horizontally upon the frame 10, and in this movement when 50 the pins C are placed therein in inclined positions with their lower ends resting in the openings in said frame the rack will bring the pins automatically to upright position so that they, by their own weight, will drop 55 through the openings 18 in the frame 10 and the guide 19 will automatically operate to center said pins C exactly over the pin spots upon the alley and bring the same to true upright position for the setting of the 60 said pins. On the raising of the frame 10 which is effected in the usual manner the rack 17 will move automatically and horizontally back to normal position, shown in Fig. 3 of the drawings, and when in nor-

mal position will again be in position to receive the bowling pins C which will be automatically set when the mechanism is again operated. When the frame is lifted the weight of the shoes or equivalent means will return the pin tray to its original or normal 70 position.

The invention also includes modifications of mechanism and equivalent means protected by the scope of the claims.

Having thus described our invention, we 75 claim:

1. In a pin setting apparatus for a bowling alley, the combination of a vertically movable lower frame having pin discharging openings therein, a shifting frame slideable thereon in a horizontal plane and having corresponding openings, bell cranks pivoted in said vertically movable frame a corresponding number of shoes vertically movable in said lower frame, a link connecting each shoe with one of said bell cranks, and a link connecting each bell crank with said shifting frame, said shoes operating to rotate said bell crank to move said shifting frame horizontally over said lower frame, when said lower frame is lowered to engage said shoes with the floor of said alley. 85

2. In a pin setting apparatus for a bowling alley, the combination of a vertically movable lower frame having pin discharging openings therein, a shifting frame slideable thereon in a horizontal plane and having corresponding openings, bell cranks pivoted in said vertically movable frame a corresponding number of shoes vertically movable in said lower frame, a link connecting each bell crank with said shifting frame, said shoes operating to rotate said bell crank to move said shifting frame horizontally over said lower frame when said lower frame is lowered to engage said shoes with the floor of said alley, positioning means for said lower frame, and a separate positioning means for each pin, substantially as described. 95

3. In a pin setting device, in combination, a vertically movable lower frame, a shifting frame, a horizontal track upon the lower frame upon which said shifting frame is reciprocable in a horizontal plane, shoes having stems vertically movable in said lower frame, a bell crank pivoted in said lower frame for each shoe, links connecting said bell cranks and shoes and links connecting said bell cranks and shifting frame, whereby when said frames are lowered said shoes will engage the alley floor and operate said bell cranks to move said shifting frame, said shifting frame automatically returning to the starting position when said frames are raised. 115

4. A bowling alley pin setter comprising a vertically movable frame, means for guid-

- ing the frame into vertical movement, a pin rack slideable upon the frame for uprighting bowling pins placed therein, and means for automatically shifting the pin rack on the 5 raising and lowering of the frame.
5. A bowling alley pin setter comprising a vertically movable frame, means for guiding the frame into vertical movement, a pin rack slideable upon the frame for uprighting 10 bowling pins placed therein, means for automatically shifting the pin rack on the raising and lowering of the frame, and means carried by the frame for bringing the pins to vertical and spotting positions.
- 15 6. A bowling alley pin setter comprising a vertically movable frame, means for guiding the frame into vertical movement, a pin rack slideable upon the frame for uprighting bowling pins placed therein, means for automatically shifting the pin rack on the raising and lowering of the frame, means carried by the frame for bringing the pins to vertical 20 and spotting positions, and means swingingly connecting the last named means to the frame.
- 25 7. A bowling alley pin setter comprising a vertically movable frame, means for guiding the frame into vertical movement, a pin rack slideable upon the frame for uprighting bowling pins placed therein, means for automatically shifting the pin rack on the raising and lowering of the frame, means carried by the frame for bringing the pins to vertical 30 and spotting positions, means swingingly connecting the last named means to the frame, and means for movably supporting the frame.
- 35 8. A bowling alley pin setter comprising a vertically movable frame, means for guiding the frame into vertical movement, a pin rack slideable upon the frame for uprighting bowling pins placed therein, means for automatically shifting the pin rack on the raising and lowering of the frame, means carried by the frame for bringing the pins to vertical 40 and spotting positions, means swingingly connecting the last named means to the frame, means for movably supporting the frame, and shoes carried by the rack operating means and engageable with the bed of a bowling alley.
- 45 9. In a bowling pin setter, in combination a frame, complementary guiding and positioning means upon said frame and alley, a horizontal slideable pin rack mounted upon 50 said frame and containing pin receiving openings, said frame provided with pin positioning openings through which the pins fall by gravity when moved by said rack to the vertical position, and means for automatically operating said slideable pin rack when the frame is lowered into position above said alley, said means comprising vertically movable shoes, adapted to rest upon the alley and means operatively connecting 65 said shoes, frame and pin rack for giving a horizontal sliding movement to said rack upon said frame when the weight of said frame is received upon said shoes.
10. In a bowling alley pin setter, in combination with said alley, a frame vertically movable over said alley, guide means upon said frame and registering guide means in said alley, a horizontally slideable pin rack upon said frame, and means engaging said alley and operatively connecting said rack 70 and frame for giving a horizontal sliding movement to said rack.
- 15 11. In a bowling alley pin setter, in combination with said alley, a frame vertically 80 movable over said alley, guide means upon said frame and registering guide means in said alley, a horizontally slideable pin rack upon said frame, and means engaging said alley and operatively connecting said rack 75 and frame for giving a horizontal sliding movement to said rack, and guide means operated by contact with the surface of said alley for accurately placing said pins and said guide means withdrawn by gravity 85 when said frame is raised.
- 20 12. In a bowling alley pin setter, in combination with said alley, a frame vertically 90 movable above said alley, and provided with pin depositing openings, vertical pins projecting from the lower side of said frame, complementary socket members inserted in said alley, a pin rack upon said frame, vertically 95 sliding alley engaging shoes in said frame, and means operatively connecting said frame, shoes and pin rack, whereby said frame, shoes and pin rack, whereby said 100 pins will operate to give said rack a horizontal sliding movement upon said frame, when said frame is lowered.
- 25 13. In a bowling alley pin setter, in combination with said alley, a frame vertically 105 movable above said alley, and provided with pin depositing openings, vertical pins projecting from the lower side of said frame, complementary socket members inserted in said alley, a pin rack upon said frame, vertically 110 sliding alley engaging shoes in said frame, and means operatively connecting said frame, shoes, and pin rack, whereby said shoes will operate to give said rack a horizontal 115 sliding movement upon said frame, when said frame is lowered, and vertical guides in which said shoes move.
- 30 14. In a bowling alley pin setter, in combination, a frame, a horizontally slideable pin rack thereon, horizontal guide means for said pin rack on said frame, said frame and rack provided with openings through which said pins fall when the rack is moved to setting position, weighted shoes adapted to rest upon said alley when the frame is lowered, link and lever mechanism operatively connecting said shoes frame and rack where- 120
- 35 125

21
by when said frame is lowered said pin rack will move horizontally on said frame, the weight of said shoes causing the return of said rack to its normal position when the 5 frame is raised.

15. In a pin setting device for a bowling alley, the combination with said alley, of a frame vertically movable thereon, said frame and rack having pin depositing 10 openings, a pin rack movable thereon, a po-

sitioning device for the frame comprising complementary registering guide means upon said frame and alley, and pin positioning means projecting from the lower side of said frame.

15
In testimony whereof we affix our signatures.

WILL T. STATES.
HERBERT F. LAPP.
